CLAIM

The ornamental design for display container for toys or similar article, as shown and described.

[21] Appl. No.: 17,220

DESCRIPTION

[22] Filed: Mar. 5, 1979

FIG. 1 is a front view of a display container for toys or similar article, showing our new design;
FIG. 2 is a side elevational view, the opposite side being substantially a mirror image thereof;
FIG. 3 is a rear elevational view;
FIG. 4 is a bottom plan view of the article of FIG. 1; and
FIG. 5 is a top plan view thereof.
